UNITED STATES PATENT OFFICE.

JOHN AUGUSTUS ENOS, OF PEABODY, ASSIGNOR OF TWO-THIRDS TO
MATTHEW H. ROBINSON, OF QUINCY, AND ORLANDO A. FOSTER,
OF SALEM, MASSACHUSETTS.

SUSPENSION-RAILWAY AND CAR-HANGER.

SPECIFICATION forming part of Letters Patent No. 331,387, dated December 1, 1885.

Application filed April 24, 1885. Serial No. 163,309. (No model.)

To all whom it may concern:

Be it known that I, JOHN AUGUSTUS ENOS, a citizen of the United States, residing at Peabody, in the county of Essex and State of Massachusetts, have invented certain new and useful Improvements in Suspension-Railways and Car-Hangers, of which the following is a description.

Figure 1 is a side elevation showing the relation of the truck, track, hanger, and car, with parts of the hanger broken away. Fig. 2 is a vertical cross-section of the same. Figs. 3 and 4 are views taken at right angles to each other, and on an enlarged scale, of the lower portion of the hanger. Figs. 5, 6, and 7 are details showing modifications.

The object of my invention is to provide an improved suspension-railway and car-hanger designed to sustain a street passenger-car from a point above its center of gravity, and yet allow the car to be close enough to the curb or level of the sidewalk to allow passengers to get on or alight from the car in the usual way.

It consists in such peculiar construction of the elevated railway and its combination with the hanger-truck for sustaining the car and causing it to travel along on said track and climb grades in a safe and smooth manner as will be hereinafter more fully described.

The car itself I have made the subject-matter of a separate application, filed this same day, and while not claimed herein, it is shown for the purpose of rendering the connections and mode of operation of the other parts more apparent.

In the drawings, Figs. 1 and 2, A represents an iron post or standard, which is buried at its lower end in the sidewalk, and has its end bolted and securely braced to a metal shoe that is bolted to a granite block. At the top of this post are two horizontal projecting bars, B B', about four and a half feet apart, and a diagonal brace, B''. To the outer ends of these bars is attached a vertical trestle-work of iron, composed of crossed diagonal bars B³, vertical bars, B⁴, and horizontal bars, B⁵. On the upper side of this trestle-work is laid a continuous wooden stringer, C, having

thereon a continuous rail, C', and to the lower side of the trestle-work is attached a continuous wooden stringer, C², to which is attached a continuous rail, C³. The upper rail is designed to support the weight of the car through a truck, and the lower rail is designed to act as a guide in connection with wheels on the hanger or the car, to prevent it from swaying about, and to provide means also for enabling the car to climb grades, as hereinafter described. The car is sustained upon the upper rail by a truck, D, whose particular construction is described and claimed in another application of even date herewith. This truck has two sets of pendent hanger-bars, F F, each of which passes down to and is securely riveted or bolted to a curved metal arm, E. This arm is curved so as to bring its point *x* of articulation with the car exactly under the wheels of the supporting-truck. One set of hanger-bars F connect with or support the front end of the car, and the other set of bars F connect with and support the rear end of the car, and between the two points there is a raised inclosure, P, in which is located the motor for driving the car, which is an electric motor adapted to take the current from two continuous conductors located on the trestle-work by means of suitable brushes or rollers in a manner well known to electricians, and which motor transmits its driving-power to the wheels of the upper supporting-truck through the chain G, which passes around the gear-wheels of the supporting-truck.

I will now describe the means for guiding the car and preventing it from swaying from the wind or other cause, and enabling it also to climb grades.

To the point where the car is jointed to the curved bar E, and at each end thereof, there is attached an upwardly-projecting bar, E', (see Fig. 3,) which at its upper end is riveted to a horizontal plate, E², that is also riveted to the curved bar E, so as to form a strong frame-work. From this plate E² there rises two yoke-pieces, G' G', Figs. 3 and 4, between which and the plate E² are arranged four guide-posts, G⁵, on which are guided the two journal-boxes G² G³, which sustain a shaft, G³, car-

rying the flanged guide-wheel G^4 , that runs against the lower rail.

Between the journal-boxes G^2 and the plate E^2 and around the guide-post G^5 are disposed spiral springs H , which serve to press the pulley G^4 upward against the rail with a gentle steady pressure. The shaft G^3 of the pulley is extended out on each side beyond its journal-boxes, and is provided with an enlarged head, between which and the journal-boxes a spiral spring, G^6 , is arranged, which allows for a slight lateral sway of the car and the hanger-bar F without disconnecting the flanged guide-wheel from the rail.

To hold the car steady against swinging about the joint at the lower end of the curved bar E , guy-rods I run from the top of curved bar E to the sides of the car on each side, and at the car they pass through brackets b , Figs. 1 and 2, and terminate in heads a , and between the brackets and a collar, c , on the rods a spiral spring, d , is wound, which is kept in compression and forms a yielding connection to hold the car stiffly about its suspending joint, the heads on the ends of the guy-rods serving to limit the motion which these springs allow by striking against the under side of the bracket.

To the two journal-boxes of the wheel G^4 the two arms $e e$, Figs. 3 and 4, of a vertical bar, J , are attached, which bar J is connected at its lower end to the short end of a lever, K , which is fulcrumed at f to the frame $E E'$, and extends to a position at one end of the car, (see Fig. 1,) to be operated upon by a pull-rope. By pulling this rope and the lever the journal-boxes of the wheel G^4 are thrown upwardly, and the wheel is pressed more forcibly against the lower rail. This, it will be seen, causes the truck-wheels above to impinge more tightly on the upper rail by a downward pull on the hanger-bar F , or, rather, causes the two rails to be more tightly pinched by the upper and lower track wheels, which gives a greater friction and increased tractive power for climbing grades.

With respect to the use of the lower rail and its wheel G^4 , this is mainly to act as a guide to keep the car from swinging about its point of support on the upper rails. Its effectiveness for this purpose is dependent upon the distance it is located below the upper truck. I prefer to use it as shown, for while it sufficiently guides the car and prevents swaying it serves the additional function of enabling me by the mechanism just described to climb grades by varying the tractive power of the wheels on the rails. I may, however, in some instances locate this guide-rail and wheel G^4 at the side of the car, as shown in Fig. 7, or at the bottom of the car, as shown in Fig. 6, or I may arrange said rail in the same relation to the trestle-work as in Fig. 2, but construct it with a deep web, and have two anti-friction rollers to engage with it from opposite sides, as shown in Fig. 5.

To permit the joint x at the lower end of the frame E to rock slightly, lengthwise the car, in going up and down hill, the eyes h , Fig. 4, of the frame $E E'$ and the eye j of the iron k on the car are made slightly rounding where they bear against each other, and the holes through the same are made with a corresponding taper.

Having thus described my invention, what I claim as new is—

1. The combination of a single elevated rail and a truck with a set of wheels arranged in the same plane and mounted thereon, a curved hanger depending therefrom, a car fastened to the hanger immediately beneath the vertical line of the supporting-truck wheels, and a subjacent track and guide-wheel, arranged as shown and described, to prevent the swaying of the car about its upper supporting-rail. 85

2. The combination of an elevated rail or track, a supporting-truck mounted thereon and provided with a curved hanger-bar, a car fastened to the hanger in the vertical line of the truck-wheels, and a lower rail and guide-wheel arranged in the vertical line of the upper rail, the said guide-wheel being connected to the hanger, substantially as shown and described. 90

3. The combination, with the post A , the horizontal bars $B B'$, and diagonal brace B^2 , of the vertical trestle-work $B^3 B^4 B^5$, the upper and lower stringers, C and C^2 , and the upper and lower rails, C' and C^2 , substantially as and for the purpose described. 100

4. The combination, with the upper and lower rails, $C' C^2$, of the hanger having a supporting-truck at its upper end, a car attached to its lower end, an adjustable guide-wheel bearing against the lower rail, and means, substantially as described, for increasing the pressure of this guide-wheel against its rail to increase the friction and tractive power of the trucks for climbing grades, as described. 110

5. The combination of the upper and lower tracks, the hanger F , having a supporting-truck at its upper end and a car attached to its lower end, the curved bar E and framework $E' E'$, plates E^2 with yokes G' and posts G^5 , the guided and vertical adjustable journal-boxes G^2 , springs H , and the shaft G^3 and pulley G^4 , substantially as shown and described. 115

6. The combination, with the hanger F and the guide-rail C^3 , of the guide-wheel G^4 , having its shaft extended beyond its journal-boxes and provided with springs G^6 , as and for the purpose described. 120

7. The combination, with the hanger-frame $E E'$, of the lever K , rod J , having arms $e e$, and the guide-wheel G^4 , having its journal-boxes attached to the arms $e e$, as and for the purpose described. 125

8. The combination, with the car and its hanger having a point of articulation at x , of the guy-rods I , having spring-seated or elas-

tic connections with the car at their lower ends.

9. The combination, with a single track-rail, of a suspended passenger-car, a curved hanger-bar, a truck attached to the upper end of the hanger-bar, and having a set of spring-seated wheels arranged in the same plane and

suspended on said rail, and means for moving thereon, substantially as described.
